UNITED STATES PATENT OFFICE.

MARCUS FEDER, OF CLEVELAND, OHIO.

DESIGN FOR A BOX.

SPECIFICATION forming part of Design No. 28,141, dated January 11, 1898.

Application filed November 5, 1897. Serial No. 657,573. Term of patent 7 years.

To all whom it may concern:

Be it known that I, MARCUS FEDER, a citizen of the United States, residing at Cleveland, in the county of Cuyahoga and State of Ohio, have invented and produced a new and original Design for Boxes; and I do declare the following to be a full, clear, and exact description of the same, reference being had to the accompanying drawings, forming a part thereof.

My invention relates to a design for boxes, and will be fully understood from the following description and claim when taken in conjunction with the annexed drawings, in which—

Figure 1 is a perspective view of a box, showing my new design. Fig. 2 is a transverse section of the same.

The leading or material feature of my design consists of the ribs or projections A on the top of the cover B of the box, alined with similar ribs or projections C on the front and back of the cover, which in turn are alined with similar ribs D on the front and back of the body E of the box, the said ribs D having their lower ends arranged flush with the bottom of the box, which is plain, as shown in Fig. 2.

As shown in Fig. 1, the ribs or projections A rest parallel with the ends of the box at a short distance from the same and have their ends flush with the upper ends of the ribs C, so as to make a neat finish. The said ribs or projections C are disposed in the direction of the height of the box and also parallel with the ends thereof, as are also the ribs or projections D, which aline with the ribs C. Consequently it will be seen that when the box is closed the several ribs A C D will present the appearance of two continuous ribs resting in parallel planes and extending from the bottom of the box up the front and back and across the top thereof.

Having thus described my design, what I claim as new, and desire to secure by Letters Patent, is—

The design for a box as herein shown and described.

In testimony whereof I affix my signature in presence of two witnesses.

MARCUS FEDER.
